UNITED STATES PATENT OFFICE.

CLAUDE E. KRAMER, OF VAN BUREN, INDIANA.

DEVICE FOR CLEANING PIPE-THREADS.

1,071,242.

Specification of Letters Patent. Patented Aug. 26, 1913.

Application filed January 25, 1913. Serial No. 744,113.

To all whom it may concern:

Be it known that I, the undersigned, CLAUDE E. KRAMER, a citizen of the United States, residing at Van Buren, in the county 5 of Grant and State of Indiana, have invented certain new and useful Improvements in Devices for Cleaning Pipe-Threads, of which the following is a specification.

This invention relates to devices for the 10 cleaning of pipe-threads.

In the business of transporting, handling and trafficking in pipes of the larger sizes, such as two, three, four, five and six inch pipe and even larger sizes, used in the development of and operations on of gas and oil lands, the threads on the pipes and the threads of the pipe couplings, become clogged and filled with dirt, gum and foreign substances. Ordinarily this condition 20 is not one of great difficulty, but when the time comes that a market may be sought for used or second-hand pipe of the kind described, the most important consideration is that of the condition of the threads. As the 25 market value of the pipe depends almost solely upon the condition of the threads it is essential that the threads may be effectively cleaned. Moreover, the work of cleaning same must be done rapidly and economically.

The character of pipe and coupling, upon which this invention is especially intended to operate, is that shown in Figure 4 of the drawings. In the use and handling generally of this class of pipe there may be accumulation of dirt, grease, grit and the like in the threads of the coupling 2, not only throughout the portion near the edge of the coupling, but at the threads farthest in, and entirely to the end of the pipe 1. To 35 manually clean these threads by the use of ordinary chasing tools or implements is not only tedious and expensive but is ineffective owing to the difficulty of getting at the threads in a manner to dislodge the dirt and grit throughout their entire extent.

Accordingly therefore the objects of this invention are to provide a device or implement to facilitate the work of cleaning the threads, and to render possible the doing of 45 this work effectively by a person of only ordinary skill.

More specific purposes are to provide features of improvement in construction, and to afford a device which will be simple of

construction, economical of manufacture, 55 durable and not liable to get out of repair.

These objects are accomplished by the new construction, combination and arrangement of parts illustrated in the accompanying drawings, described in this specification, 60 and defined in the appended claims.

In the drawings: Fig. 1 is a side view, and Fig. 2 is a top plan view of my improved thread cleaner complete. Fig. 3 is a sectional plan view taken on the line 3—3 65 in Fig. 1. Fig. 4 is a view showing a pipe coupling of the character for the cleaning of which my present invention is especially adapted. Fig. 5 is a modification showing the relative positions of the chasing member 70 and pilot members, when the device is to operate upon external threads.

The body A made of metal is of the general form and proportion as shown and has the shank A¹ angular in cross section and 75 adapted to be engaged by a means for turning or rotating same, such as a carpenter's brace. Extending radially from the body A and to which body their inner ends are secured, are pairs of threaded arms B and 80 B, C and C and D.

Members E, F and G made preferably of steel and which are of form and section to have the proper resiliency, have their shank portions E¹, F¹ and G¹ provided with suitable holes so that the said members may be passed to position on the arms B and B, C and C, and D and D respectively. These members are held at desired adjusted positions by nuts H, as plainly shown in Fig. 1 85 and Fig. 2. The member E is so formed at and Fig. 2. The member E is so formed at its free end that when the chaser die K is secured thereto the threaded or cutting side of the die is at proper alinement to engage the threads to be cleaned. The preferable 90 construction of the above feature consists in bending the lower portion E² of the said member E to substantially a right angle. The chaser die K may be of the size and proportion shown and is secured by bolts L. 100

The functions of the members F and G are to act as pilots and bearing members whereby the movement of the chaser die will be steadied and the die will be pressed or urged to proper contact with the threads 105 of the coupling. To accomplish the best result, the formation of the ends of these members F and G is that shown in Fig. 1.

The portions F^2 and G^2 are bent slightly outwardly thence in alinement with the body of the member, and thence are turned inwardly and have the rounded noses G^3 5 and F^3 .

The utility of my invention is apparent and the mode of practising same will be readily understood. The lengths of the arms B, C and D are sufficient that the device 10 may be used on material of the larger as well as the smaller diameters. To adapt the device to the size of the material to be operated on, the nuts H are loosened and the members E, F and G are disposed at 15 correct locations. With the nuts H then tightened these members will be held securely.

A brace, or other suitable hand-operable means for rotating the device is then applied to the shank A¹. The noses F^3 and 20 G^3 facilitate the entry of the device into the coupling.

With a rotary movement of the device the chaser die immediately enters the thread 25 of the coupling. The position of the chaser die, and the action of the members E and F are such that although the threads of the chaser die closely engage the threads of the coupling, there is a sufficient yield thereto 30 that liability of breakage or derangement of the device is reduced to a minimum. By simply rotating this device the threads of the coupling may be thoroughly chased and cleaned. When nearing the end of the 35 thread, the noses F^3 and G^3 engage and permit the members F and G to draw inwardly and to pass the end of the pipe, the chaser die being thus permitted to traverse the thread in the coupling entirely to the end of 40 the pipe.

Ordinarily one traversing of the thread will effectively cleanse same. However, in cases where the sediment in the thread has become hard and the metal corroded, repeated 45 traversing of the threads may be necessary. To withdraw the device to initial position same is rotated in the opposite direction, or, in the smaller sized devices, it may be drawn slightly to one side and drawn di-

rectly. The raised faces F^2 and G^2 of the members F and G constitute bearings for said members against the threads, of limited frictional area, and permits of the most effective action of the said members as springs to hold the chaser die firmly and at 55 the same time yieldably at engagement with the threads.

To adapt this invention to operate upon the thread of the pipe, the members E, F and G are simply placed on the arms B—B, 60 C—C and D—D in positions reversed to the positions shown in Figs. 1 and 2. With the invention so adapted, the relative positions of the members E, F and G are as shown in Fig. 5. The manner of operating the invention in this modification thereof, is the same as hereinbefore described.

What I claim as my invention is:—

1. A thread cleaning device, comprising a body, radial arms carried by the body, 70 resilient members carried by the said arms and whose free ends are adapted to have bearing against the threads, means to hold the said members at varied adjusted positions on said arms, and a chaser carried by one of the said 75 resilient members.

2. A thread cleaning device, comprising pairs of radial arms carried by the body, resilient members carried by the said pairs of arms and whose free ends are adapted to 80 have bearing against the threads, means to hold said members adjustably in connection with each of said arms, and a chaser carried by one of the said resilient members.

3. A thread cleaning device, comprising 85 pairs of radial threaded arms carried by the body, resilient members having holes in their upper portions that are engaged by the said radial arms, lock nuts for each of said resilient members, and a chaser carried on 90 the free end of one of the said members.

In testimony whereof I affix my signature in presence of two witnesses.

CLAUDE E. KRAMER.
